UNITED STATES PATENT OFFICE.

ALFRED M. BERRY, OF BELLOOSE, NEW YORK, ASSIGNEE TO INTERTYPE CORPORATION, OF NEW YORK, N. Y., A CORPORATION OF NEW YORK.

ELEVATOR FOR TYPOGRAPHICAL MACHINES.

Application filed February 11, 1928. Serial No. 253,682.

The present invention relates to improvements in typographical machines of the general class shown and described in Letters Patent No. 436,532 granted September 16,

5 1890, to O. Mergenthaler wherein character bearing matrices are drawn from a magazine and assembled in a line under control of a keyboard and the matrix line is conveyed to a position in front of a mold in which a type 10 bar is cast, after which the matrix line is lifted by a so-called second elevator to a distributing mechanism which returns the matrices to the respective channels of the magazine.

15 The invention is more particularly applicable to machines of this general class which have been adapted to contain two or more matrix magazines to deliver matrices to the lines during composition and which have individual distributors for returning the 20 matrices to the magazines from which they were drawn, and a shiftable distributor box for directing the returning matrices to their respective distributors, distributing mechanism of this kind being shown in and described in Letters Patent No. 1,202,719 granted October 24, 1916, to T. S. Homans.

The primary object of the invention is to provide novel means for accurately alining 30 matrices lifted by the second elevator with the matrix guiding and supporting means of the distributor box so as to insure proper transfer of the matrices from the second elevator to the distributor box irrespective of the position occupied by the latter with respect to the different distributors, and for maintaining such alinement during the shifting movements of the distributor box from one distributor to the other.

40 To these and other ends the invention consists in certain improvements and combinations and arrangements of parts all as will be hereinafter more fully described, the features of novelty being pointed out particularly in the claims of the specification.

In the accompanying drawings:—

Fig. 1 is a side elevation of the second elevator of a typographical machine and showing in transverse section distributing mechanism 50 for a plurality of magazines and the transfer channel from which the matrices are lifted by the second elevator;

Fig. 2 is a detail view partly in section and

on an enlarged scale, showing the matrix supporting bar of the second elevator and the distributor box arm and the means thereon for alining the bar of the second elevator;

Fig. 3 is a front elevation partly in section, showing the distributor box and the pivoted distributor box arm, the matrix supporting 60 bar of the second elevator being shown alined with the distributor box;

Fig. 4 is a top plan view partly in section, showing the matrix carrying bar of the second elevator swung into alinement with the distributor box when the latter is positioned to direct the matrices into one of the distributors;

Fig. 5 is a view similar to Fig. 4 but showing the matrix carrying bar of the second elevator alined with the distributor box while the latter is swung into position to direct matrices to another distributor;

Fig. 6 is a detail view, partly in elevation and partly in section, showing the pivoted or swivelled mounting of the matrix carrying bar on the link of the second elevator arm, and

Fig. 7 is a detail perspective view of the matrix carrying bar and the link which supports it on the second elevator arm.

Similar parts are designated by the same reference characters in the several figures.

The present invention is applicable generally to typographical machines of the class employing two or more magazines having individual distributors for returning the matrices to the respective magazines, although the invention is especially applicable to machines of the general class shown and described in the Mergenthaler patent hereinbefore referred to. Also, the invention is especially applicable to plural magazine machines having distributing mechanism embodying a distributor box which is shiftable 85

automatically or otherwise from one distributor to another, during the distribution of the matrices, effecting return thereof to the appropriate magazines, as for example is accomplished by the distributing mechanism shown and described in the Homans patent hereinbefore referred to. The preferred embodiment of the invention is shown in the accompanying drawings and will be hereinafter described in detail but it is to be understood that the invention is not restricted to the 90

precise construction shown and described as 100

105

equivalent constructions may be used and such will be included within the scope of the claims.

In the present instance 1 represents a portion of the distributor bracket of a typographical machine of well known construction and of the general class hereinbefore referred to, this distributing bracket supporting distributing mechanism for a plurality of matrix magazines, the distributing mechanism in the present instance comprising a pair of distributors which embody the respective combination or distributor bars 2 and 3 along which the matrices travel while suspended therefrom in the usual and well known way, the travel of the matrices along the distributor bars being effected by the usual distributor screws 4. It will be understood that channel entrances such as those commonly used in machines of this class serve to conduct the matrices dropping at different points along the distributor bars 2 and 3 to the appropriate matrix channels of the respective magazines the upper or entrance ends of which are positioned as usual below the distributing mechanism.

The transfer channel 5, which is positioned at the front of the machine, in machines of this class, receives each line of matrices and spacers from the so called first elevator of the machine after a type bar has been cast from such line, and while the matrix line is being introduced into the transfer channel, the matrices M become engaged on the ribbed bar 6 which is fixed to a plate 7, the latter then resting on the top of the transfer channel 5 so that the ribbed bar 6 projects down into the channel so that the teeth in the recesses in the upper ends of the matrices may become engaged with the ribs on this bar in a manner which is well known and which causes the matrices to become suspended from the bar 6. The spacers in the line have untoothed notches in their upper ends so that they do not become attached to the bar 6 but remain in the transfer channel 5 and after removal of the matrices from the transfer channel, the spacers are swept along the channel to the usual space band box.

The matrices are lifted from the transfer channel to the distributing mechanism by the so called second elevator which comprises an arm 8 which carries the matrix supporting bar 6, the second elevator arm being usually pivoted at 9 to a relatively fixed bracket 10 which is immovably secured to or forms a part of the frame of the machine, and the arm 8 is swung through a suitable angle and at appropriate intervals under the control of a second elevator cam 11 which is fixed to the main cam shaft 12 of the machine, the arm 8 having a link 13 pivotally connected to it at 14 and the bracket 10 having a link 15 pivotally connected to it at 16, these links being pivotally connected to one another at 17 and one of the

links, the link 15 in the present instance, having a roller 18 mounted thereon and arranged to ride on the periphery of the cam 11 the shape of which determines the time and extent of swing of the second elevator.

The matrix supporting bar 6 of the second elevator is connected to the second elevator arm 8 by a link 19 which preferably straddles the free end of the second elevator arm and is pivotally connected thereto by the transverse pivot pin 20, and the link 19 is acted on by a tension spring 21 one end of which is fixed to the second elevator arm 8 and the other end of which engages a hook 22 on the upper or rear end of the link 19. This spring serves to hold the matrix engaging means on the link 19 against a guide 23 secured at the forward side of the transfer channel 5 so that the matrix receiving bar 6 will enter the transfer channel in proper position to receive the matrices as they are introduced therein from the first elevator and also to allow the matrix supporting bar 6 to stop in its ascent when it reaches the proper elevation in relation to the distributor mechanism, as will hereinafter appear.

In the present instance two distributors are provided for the return of matrices to two magazines, the matrix supporting bars 2 and 3 of these distributors being spaced one beside or in front of the other although they are both at substantially the same height, and the matrices are directed to one or the other of these distributors from a distributor box 24 which is mounted on an arm 25 which is pivoted to swing laterally or in a horizontal plane about a vertical pivot pin 26, the latter being secured to a beam 27 which is a relatively fixed part of the distributor mechanism. The distributor box arm 25 is provided with a guideway in which a slide 28 may reciprocate under the action of a pitman 29, the slide carrying a head or buffer 30 which is arranged to engage the end of a matrix line when the latter has been elevated by the second elevator and to push the matrices from the bar 6 of the second elevator into the distributor box, and the latter is provided with the usual matrix lifter for lifting the matrices successively into engagement with the appropriate distributor arm 2 or 3, and means may be provided, such for example as that shown and described in the Homans patent hereinbefore referred to, for automatically shifting the distributor box to deliver the matrices to one of the other of the distributors, according to the fonts to which the matrices belong.

The distributor box arm 25 is formed at its under side with a flat face 31 against which the top of the plate 7 is adapted to abut, when the second elevator is raised, the surface 31 thus positioning the matrix supporting bar 6 at the proper level to register or align it vertically with the matrix supporting rails in the distributor box, and the rear portion of

the distributor box arm 25 is formed with a pair of similar lugs 32 which are spaced along the length of the distributor box arm so that the upper or free end of the second elevator arm 8 and the link 19 may pass between them without obstruction. These lugs cooperate with the rear edge of the plate 7, during the final portion of the elevating movement of the second elevator and thereby align 5 the matrix supporting bar 6 horizontally with respect to the matrix receiving and supporting rails in the distributor box. Preferably, the forward sides of the lugs 32 adjacent to the alining surface 31 are recessed as at 33 and the lower wall of each recess is bevelled as at 34, and the rear edge of the plate 7 is shaped to enter the recesses 33 and has a bevel 35 on its under side to cooperate with the bevelled walls 34 of the lugs. These bevelled surfaces on the lugs and the plates 7 insure accurate alinement of the matrix supporting rail 6 with respect to the distributor box, as the final portion of the ascending movement of the second elevator causes the 10 rear edge of the plate 7 to enter the recess 33 in the lugs, and as the bevelled surface 35 on the plate 7 engages the bevelled surfaces 34 on the lugs, the plate 7 will be forced upwardly so that its upper surface is caused to 15 bank solidly against the horizontal alining surface 31, thereby insuring accurate alinement of the bar 6 vertically with respect to the distributor box, and as the bevelled surface 35 of the plate 7 comes to final rest 20 against the bevels 34 on the lugs 32, the bar 6 will be accurately aligned horizontally with respect to the distributor box.

To enable the matrix supporting bar 6 and plate 7 of the second elevator to align accurately both vertically and horizontally, with the distributor box, irrespective of whether the distributor box is set to deliver matrices to one distributor, as in Fig. 4 or is in a reverse position to deliver matrices to 25 the other distributor, as in Fig. 5, the bar 6 and plate 7 are pivotally mounted on the link 19 so that they may swing freely but as a unit on two different axes which intersect or are in right angular relation. This pivotal mounting, according to the present invention, comprises preferably a block 36 having trunnions or pivot pins 37 which are alined with one another and project from its opposite ends, these trunnions or pivot pins fitting rotatably in bearings 38 which are formed on a fork-like portion of the link 19. The block 36 rests on the top of the bar 6 and it is pivoted to rock thereon about a pivot pin 39 which is fixed in the bar 6 and forms a vertical pivot about which the block 36 may rock. The trunnions or pivots 37, which are arranged horizontally and extend longitudinally of the matrix supporting bar 6, enable this bar and the plate 7 attached to it to rock about a horizontal axis so that 40 the plate 7 may seat properly on the top of the transfer channel 5 when the second elevator is lowered and the top of the plate 7 may seat solidly against the alining surface 31 of the distributor box arm when the second elevator is elevated, and the vertical pivot 39 for the block 36 enables the bar 6 to swing about a transverse vertical axis and thus accommodate the plate 7 to the alining lugs 32 and thus align the bar 6 horizontally with the distributor box, irrespective of the position into which the latter may be swung. The block 36 may be held in place on the bar 6 by fitting it between the top surface of the bar 6 and a wall 40 which is an integral portion of the plate 7, the block 36 being contained in a recess formed in the under side of the plate 7, and the upper edge of the bar 6 and the parts 6 and 7 being secured together firmly by screws 41 or other suitable means. The forward edge of the plate 7 is preferably recessed to receive the guide 23 and is provided with a vertical guard 42 to bank against the guide 23 and thereby position the matrix supporting bar 6 in proper position to receive the matrices, this guard being fixed to the plate 7 by a lug 43 which may be formed integrally with the guard and secured firmly to the top of the wall 40 of the plate 7 by the screws 41. 45 By mounting the matrix supporting member of the second elevator on the arm thereof so that said member is free to swing on a vertical axis transverse to said member, the latter is able to align itself accurately with the distributor box irrespective of whether the distributor box is set to direct matrices into one or the other of the distributors, and when the second elevator descends to receive another matrix line delivered from the first elevator to the transfer channel, the matrix supporting bar will be easily swung into parallelism by the banking of the guard plate 42 against the guide 23. Preferably, a tension spring 45 is attached at one end to the rear edge of the plate midway of its length, 50 as by the hook 46, and is hooked at its opposite end in an aperture 47 in the middle of the link 19, this spring acting to yieldingly hold the bar 6 and plate 7 in approximately a middle or neutral position with respect to its pivotal motion about the pivot pin 39, and to yieldingly hold said bar and plate so that the guard 42 will be in position to properly engage the guide 23 during descent of the 55 second elevator.

I claim as my invention:—

1. In a typographical machine, an elevator for conveying matrices to matrix distributing mechanism, comprising a matrix supporting bar, a positioning member for said bar in fixed relation to it, and means pivotally supporting said bar and member to swing on an axis transverse to the length of said bar.

2. In a typographical machine, an elevator for conveying matrices to matrix distribut-

- ing mechanism comprising an elevator arm, a matrix supporting bar, a positioning member for said bar in fixed relation to it, a block pivoted to swing relatively to said bar and member on an axis transverse to the length of said bar, and means pivotally connecting said block to said arm on an axis longitudinal to said bar.
3. In a typographical machine, an elevator for lifting matrices to matrix distributing mechanism, comprising an elevator arm, a matrix supporting bar, a positioning member for said bar fixed to it, a block pivoted to swing relatively to said bar and member on an axis transverse to the length of said bar and having pivots extending therefrom in opposite directions radially from said axis, and means cooperative with said pivots for supporting said bar on said arm.
4. In a typographical machine, an elevator for conveying matrices to distributing mechanism comprising an arm, a matrix supporting bar, a positioning plate fixed to said bar, a block pivotally mounted between said bar and plate to swing relatively to said bar and plate on an axis transverse to the length of the bar, and a link carried by said arm and pivotally connected to said block on an axis longitudinal to said bar.
5. In a typographical machine, an elevator comprising a swinging arm, a matrix supporting bar, a positioning member for said bar in fixed relation to it, a block pivotally connected to said bar to swing relatively to said bar and member on an axis transverse to the length thereof, and a link carried by said arm and having a forked portion which straddles said block and is pivotally connected thereto on an axis longitudinal to the length of the bar.
6. In a typographical machine, an elevator

comprising an arm, a matrix supporting bar pivotally connected thereto on an axis transverse to its length whereby said bar may swing in either direction about said axis, and means acting to yieldingly hold said bar in position substantially midway of its swing in either direction.

7. In a typographical machine, an elevator comprising a supporting member, a matrix carrying bar pivoted to said member to swing about an axis transverse to the length of said bar, and a spring acting on said bar to swing it about said axis into substantially a predetermined position and to yieldingly retain it in such position.

8. In a typographical machine having a plurality of matrix distributors, a distributor box pivoted to swing into different angular positions to cooperate with one or another of said distributors, and an elevator for conveying lines of matrices to the distributor box, a matrix supporting bar pivotally mounted on the elevator to swing on an axis transverse to the length of said bar, and means for swinging said bar about said axis to align it with the distributor box.

9. In a typographical machine having a matrix receiver mounted to occupy different positions angularly of its length, a matrix elevator for conveying matrices thereto embodying a matrix supporting bar along which matrices may travel longitudinally and means for supporting said bar for pivotal movement on an axis transverse to its length, and means for swinging said bar about its said axis to align it with the matrix receiver according to the angular position occupied by the latter.

In testimony whereof I have hereunto set my hand.

ALFRED M. BERRY.
